UNITED STATES PATENT OFFICE.

JAMES A. GREER, OF NEW YORK, N. Y., ASSIGNOR TO THE RAIL JOINT COMPANY, OF NEW YORK, N. Y., A CORPORATION OF NEW YORK.

RAIL-JOINT.

1,075,844.

Specification of Letters Patent. Patented Oct. 14, 1913.

Application filed February 23, 1912. Serial No. 673,404.

To all whom it may concern:

Be it known that I, JAMES A. GREER, a citizen of the United States, residing at New York, in the county of New York and State of New York, have invented certain new and useful Improvements in Rail-Joints, of which the following is a specification.

This invention relates to the subject of rail joints, and more particularly to a modified design of joint bar, of the continuous type, combined in a novel manner with a wooden filler.

A special object of the invention is to provide a structure possessing all of the advantageous features of the continuous type of rail joint, while at the same time materially augmenting the strength of the joint as an entirety, and generally improving the same, particularly as to the member thereof at the outer side of the joint.

To this end the invention contemplates a modified continuous-type of joint bar presenting a wide and effective supporting surface for the bases of the rails, and specially designed and adapted for use with a wooden or equivalent filler member with the result of providing a number of excellent features of practical importance in railway track construction.

Accordingly, the improved joint includes in its organization a novel design of joint bar whose side girder supports a wide rail supporting base, of greater width than the rail bases, which allows the inside spikes to take the lateral thrust in addition to the outside spikes. Also, this improved joint bar is intended to afford added strength to the entire outer side of the joint by reason of a novel and effective reinforcement at the top edge of the side girder. Furthermore, there is provided a wooden filler combined with the novel joint bar in such manner as to greatly reduce the noise incident to the wheels passing over the joint, and at the same time admitting of ready and easy movement of the rails in the joint under contraction and expansion, while the wooden filler also acts as a nut lock.

Another general and useful object of the invention is to provide a rail joint member, particularly adapted for the outer side of the joint, and which is inherently so effective in its rail supporting, connecting, and reinforcing functions as to admit of the use of any suitable bar or angle as the inside bar,

thus effecting a saving in the cost of the joint.

With these and many other objects in view, which will more readily appear to those familiar with the art as the nature of the invention is better understood, the same consists in the novel construction, combination and arrangement of parts hereinafter more fully described, illustrated, and claimed.

The essential features of the invention involved in the improvements above pointed out are necessarily capable of structural modification without departing from the scope of the invention, but a preferred and practical embodiment thereof is shown in the accompanying drawings, in which:

Figure 1 is a cross sectional view of a rail joint, of the non-insulated type, embodying the present invention. Fig. 2 is a detail in perspective of the novel design of joint bar, showing about one half of the bar.

Like references designate corresponding parts in the several figures of the drawings.

In carrying out the present invention, one of the distinctive objects, as above stated, is to provide a practical rail joint member which is particularly adapted for the outer side of the joint, and which admits of the use of any suitable bar or angle as the inside bar, so for illustrative purposes, there is shown in the drawings a rail joint which includes the rails R and an inside joint bar 1, that may be an ordinary angle or bar of any conventional design, and which is adapted to fit in the fishing spaces of the rails at the inner side of the joint.

The outer joint member referred to includes a joint bar 2 of a modified continuous type. That is to say, the novel bar 2 is so rolled and shaped as to form the same with an upright side girder 3, provided at its upper edge with a bearing head 4 engaging beneath the under side of the rail-heads, and at the lower edge of the said side girder or member 3, the said bar is formed with an outwardly extending and inclined foot flange 5, which overlies and bears upon the upper side of the flanges of the rails. As a part of the same integral structure, the said joint bar 2 has formed with its foot flange 5 a spiking toe 6 for the outer side of the joint, and an inwardly extending horizontal rail supporting base section 7. This rail supporting base section 7 is one of the im-

portant and practical features of the joint, inasmuch as the same is of a greater width than the width of the bases of the rails and extends entirely across the latter and projects beyond the inner edges of the rail flanges as plainly shown in the drawings. The effect of this construction is to provide a wide and uninterrupted rail supporting base for both rails throughout the entire length of the joint, thus securing a maximum supporting effect at the bottoms of the rails and contributing materially to the rigidity and strength of the joint without unduly detracting from the flexibility thereof. Also, by reason of the fact that the wide rail supporting base section 7, projects beyond the inner edges of the rail flanges and is preferably provided in such projecting part with spike openings or holes 8, the said base therefore allows the inside spikes to take the lateral thrust in addition to the outside spikes.

In addition to the elements enumerated, the upper portion of the side girder 3 has a heavy reinforcing chord which greatly strengthens said girder. This is provided for by constructing the side girder or upright member 3 with an approximately horizontal and laterally projecting reinforcing top flange 9 which is located at the top edge of the girder and is of sufficient thickness and projection so as to provide a substantial, stout and well defined reinforcement of the top part of the girder throughout the entire length of the bar. Furthermore, in the formation of this reinforcing flange or chord 9, the same is preferably formed at its under side with an inclined face 10 of greater area than the area of the under side of the rail head, thus providing for distributing the load over a surface on the compressible filler member 11 that is of aggregately much greater area than the area at the under sides of the rail heads. This condition secures a more uniform distribution of the load throughout the joint, and at the same time preserves the life and fit of the compressible member 11.

Another feature of structural importance resides in the fact that the reinforcing flange or chord 9 combines with the inclined bearing face 12 at the upper side of the foot flange 5 of the joint bar 2 to provide the said joint bar at its outer side with a longitudinal channel, within which channel closely registers the wooden or equivalent filler member or block 11. This member or block 11 has inclined or bearing surfaces 13 and

14 at the upper and lower sides thereof which respectively engage the bearing surfaces 10 and 12 of the flanges 9 and 5. The 60 filler member 11 forms a compressible backing for the metal bolt strap or washer 15 against which are tightened the heads or nuts, as the case may be, of the joint bolts 16. It will thus be observed that the wooden 65 or equivalent filler 11 presents the distinct advantage of forming a nut lock on account of its compressibility, while at the same time serving to absorb the noise as the wheels pass over the rails. Furthermore, in addition to preserving all of the desirable and practical features of the continuous type of rail joint, it will be observed that the improved construction described herein not only adds materially to the strength of the 75 joint as an entirety, and particularly to the outer bar thereof, but also presents the distinct advantage of admitting of a ready and easy expansion of the rails when the joint parts are held together in connection 80 with the compressible wood filler. Hence, the combination with the wooden filler is of special utility in this particular, as well as in the other particulars hereinbefore pointed out.

From the foregoing it is thought that the construction, action, and many advantages of the herein described rail joint will be readily apparent without further description.

I claim:

A rail joint including the rails and oppositely arranged joint bars, one of the joint bars having a longitudinal channel extending the full length of its outer side and comprising an upright side member provided at its top edge with a laterally projecting reinforcing flange and formed at the bottom with an integral horizontal rail-supporting base section of greater width than the rail bases and having a projecting spiking part beyond one edge of the rail flanges, a compressible filler member closely registering in the channel of said bar beneath the reinforcing flange thereof and projecting a distance 105 beyond the said flange, and a bolt-engaged washer plate bearing against the outer projecting part of the compressible filler.

In testimony whereof I hereunto affix my signature in the presence of two witnesses.

JAMES A. GREER.
